UNITED STATES PATENT OFFICE.

ROBERT E. POULEY, OF CHICAGO, AND ARTHUR D. POULEY, OF WAUKEGAN, ILLINOIS.

STARTER FOR INTERNAL-COMBUSTION ENGINES.

1,094,097.

Specification of Letters Patent. Patented Apr. 21, 1914.

Application filed March 18, 1912. Serial No. 684,473.

To all whom it may concern:

Be it known that we, ROBERT E. POULEY and ARTHUR D. POULEY, citizens of the United States, and residents, respectively, of 5 the city of Chicago, county of Cook, and State of Illinois, and of the city of Waukegan, county of Lake, and State of Illinois, have invented certain new and useful Improvements in Starters for Internal-Combustion Engines, of which the following is 10 a specification.

Our invention relates to improvements in starters for internal combustion engines, and has for its object a device of this character 15 which is of simple construction and efficient in operation.

Our invention consists in the combinations and arrangements of parts hereinafter described and claimed.

20 Our invention will be best understood by reference to the accompanying drawings forming a part of this specification, and in which—Figure 1 is a front elevation of a device embodying our invention, Fig. 2, a 25 rear elevation of the same, Fig. 3, a longitudinal section of the device, Fig. 4, a section taken on line $x-x$ of Fig. 3, and Fig. 5, an elevation of a valve disk employed in the device.

30 The preferred form of construction, as illustrated in the drawings, comprises a valve casing 1 provided with a standard 2 by means of which said casing may be mounted in any suitable or desired position. Casing 1 is provided with a valve chamber 3 in which is arranged a rotatable valve disk 4 having a port 5, as shown. Casing 1 is closed by a cap 6 which is provided with a plurality of ports 7, there being a port 7 for each of the cylinders of the 35 engine with which the starter is to be used. The form of construction illustrated is designed for a four cylinder four cycle engine and therefore four ports 7 arranged at angles of ninety degrees are provided. A pipe 8 connects each of the ports 7 with a corresponding cylinder of the engine, said cylinders being connected in the order in which they are normally fired.

50 A shaft 9 is rotatably mounted in casing 1, as indicated, and valve disk 4 is keyed to said shaft so as to rotate therewith. Shaft 9 is geared to the engine shaft (not shown) to run in unison with the operations of the 55 cylinders and the pistons of the engine.

Thus in the form illustrated, shaft 9 is geared to the engine shaft to run at one-half the speed thereof, so that said shaft will make one rotation for each complete operation of the cylinders and pistons. For 60 a two cycle engine, shaft 9 would be geared to run at the same speed as the engine shaft, since, in a two cycle engine, the cylinders and pistons operate in unison with the engine shaft, that is, for each rotation of the engine 65 shaft there is a complete operation of the cylinders and pistons.

The pipe 10 is connected with the valve chamber 3 in valve casing 1 and is provided with a check valve 11, as shown. Pipe 10 is 70 connected with a source of compressed air or other starting fluid (not shown) so that valve chamber 3 and consequently port 5 will be constantly supplied with said starting fluid.

In use, shaft 9 is so connected or "timed" 75 as to cause port 5 to register with each of the ports 7 successively and during the beginning and a large portion of the normal operative stroke of the piston in the cylinder connected with the corresponding port 7. In a four cylinder four cycle engine, unless the engine should happen to stop exactly on the dead center, there is always one piston which stops during this normal operative stroke, and it seldom if ever happens that a four cylinder engine stops on the dead center. This being so, and since port 5 registers with the corresponding port 7 during 80 the operative stroke of the piston in the corresponding cylinder, when the engine stops, it will stop with port 5 registering with the port 7 which is in communication with the piston which stopped during its normal operative stroke. Thus, if compressed air is supplied through pipe 10, this 85 piston and the other pistons successively will be caused to make their operative strokes by said compressed air and the engine thus started. When the engine starts 90 operating normally, the supply of compressed air to pipe 10 is cut off and the engine permitted to run under its own power. When the explosions begin in the engine 95 cylinders, the compressed air will be excluded therefrom by the high pressure therein and thus not interfere with the normal operation of the engine cylinders. Check valve 11 automatically closes to exclude the 100 high pressure in a normally operating cyl-

inder from being communicated to the source of compressed air or starting fluid.

If desired, an explosive starting fluid, such as acetylene gas, may be supplied 5 through pipe 10 and employed to start the engine. In this case the spark is preferably retarded so that the engine will normally stop "on the spark" in one cylinder, as will be readily understood by those skilled 10 in the art. In this case, when the acetylene gas is admitted to the cylinder which is "on the spark," as soon as an explosive mixture is formed, an explosion will take place and start the engine, after which each cylinder 15 will be successively supplied with the acetylene gas and the operation of the engine continued. In this instance check valve 11 prevents communication of the explosion or high pressure to the source of the acetylene 20 gas supply.

While we have illustrated and described the preferred form of construction for carrying our invention into effect, this is capable 25 of variation and modification without departing from the spirit of the invention. We, therefore do not wish to be limited to the exact details of construction set forth, but desire to avail ourselves of such variations and modifications as come within the 30 scope of the appended claim.

Having described our invention, what we

claim as new and desire to secure by Letters Patent, is:

A distributing valve comprising a casing inclosing a cylindrical chamber, one wall of said casing having an internal annular recess therein located to one side of and concentric with said chamber, the outer periphery of said recess being of less diameter than the periphery of the chamber, the wall opposite said first mentioned wall having spaced cylindrical ports disposed parallel with the axis of said chamber and registering with said recess, and the wall having said recess being provided with an inlet port substantially parallel with the axis of said chamber and opening into said recess; an operating shaft journaled concentrically in said casing; a disk carried by said shaft and snugly fitting the walls of said chamber 50 said disk having a perforation therethrough disposed parallel to and adapted to register consecutively with said cylindrical ports, substantially as described.

In testimony whereof we have signed our 55 names to this specification in the presence of two subscribing witnesses.
